PANTY GIRDLE

Herbert Barg, Merion, Pa., assignor to True Form Foundations, Inc., Darby, Pa.

Filed Oct. 5, 1970, Ser. No. 25,833

Term of patent 14 years

Int. Cl. D2—01

U.S. Cl. D2—4

FIG. 1

FIG. 3

FIG. 2

FIG. 1 is a front elevational view of a panty girdle showing my new design in flat condition;

FIG. 2 is a rear elevational view thereof; and

FIG. 3 is a side elevational view of my design in flat condition, the side opposite being a mirror image thereof.

The characteristic feature of my design for a panty girdle resides in the generally vertical stitching terminating at the lower end at the wavy horizontal stitching, all as shown on the drawing.

I claim:

The ornamental design for a panty girdle, substantially as shown and described.
